DESIGN FOR A TOY TRAILER *

Olai F. Larsen, Jr., Demarest, N. J., assignor to
Noma Electric Corporation, New York, N. Y., a
corporation of New York

Application April 3, 1946, Serial No. 128,230

Term of patent 14 years

(Cl. D34—15)

To all whom it may concern:

Be it known that I, Olai F. Larsen, Jr., a citizen
of the United States, residing at Demarest, in the
county of Bergen and State of New Jersey, have
invented a new, original, and ornamental Design
for a Toy Trailer, of which the following is a
specification, reference being had to the accom-
panying drawing, forming part thereof.

Figure 1 is a side view, Figure 2 is a top view,
and Figures 3 and 4 are opposite end views, respec-
tively, of a toy trailer showing my new design.

I claim:

The ornamental design for a toy trailer, as
shown.

OLAI F. LARSEN, JR.
